(57) **ABSTRACT**

A new cultivar of *Rhododendron* plant named 'Hort200101' that is characterized by dark shiny green leaves, dark red flowers, an absence of bracts and red branches.

1 Drawing Sheet

1

Botanical classification: *Rhododendron simsii*.
Variety denomination: 'Hort200101'.

BACKGROUND OF THE INVENTION

The present invention relates to a new and distinct cultivar of *Rhododendron* plant botanically known as *Rhododendron simsii* and hereinafter referred to by the cultivar name 'Hort200101'.

The new cultivar is the product of a breeding program conducted by the inventor in a cultivated area of Kruishoutem, Belgium. The objective of the breeding program is to develop new *Rhododendron* cultivars that have long lasting flowers and bright green leaves.

'Hort200101' is a hybrid that originated from the hybridization of the female or seed parent a proprietary selection of *Rhododendron simsii* identified as '97468' (not patented) and the male or pollen parent a proprietary selection of *Rhododendron simsii* identified as '93085' (not patented). The crossing was conducted in 2001. The cultivar 'Hort200101' was selected by the inventor in December of 2002 as a single plant within the progeny of the stated cross in a greenhouse environment of Kruishoutem, Belgium.

Asexual reproduction of the new cultivar 'Hort200101' by cuttings was first performed in December of 2002 in Kruishoutem, Belgium. Since that time, under careful observation, the unique characteristics of the new cultivar have been uniform, stable and reproduced true to type in successive generations of asexual reproduction.

SUMMARY OF THE INVENTION

The following represent the distinguishing characteristics of the new *Rhododendron* cultivar 'Hort200101'. These traits in combination distinguish 'Hort200101' as a new and distinct cultivar.

1. *Rhododendron* 'Hort200101' exhibits dark shiny green leaves.
2. *Rhododendron* 'Hort200101' exhibits dark red flowers.
3. *Rhododendron* 'Hort200101' exhibits an absence of bracts.
4. *Rhododendron* 'Hort200101' exhibits red branches.

2

The closest comparison varieties are *Rhododendron* 'Vogel Jimmy Kint' (not patented) and 'Otto' (not patented).

'Hort200101' is different than 'Vogel Jimmy Kint' in having darker green leaves, no bracts and red branches.

5 'Hort200101' has dark red flowers. The flowers of 'Vogel Jimmy Kint' are lighter red.

'Hort200101' is different than 'Otto' in having darker green leaves, no bracts and red branches. 'Hort200101' has dark red flowers. The flowers of 'Otto' are lighter red.

10 In comparison to the female or seed parent '97468', 'Hort200101' differs in having larger flowers and less frost resistance. In comparison to the male or pollen parent '93085', 'Hort200101' differs in having a more compact habit.

BRIEF DESCRIPTION OF THE DRAWING

The accompanying photograph illustrates the distinguishing traits of *Rhododendron* 'Hort200101'.

20 The plant in the photograph shows an overall view of a 24 month old plant.

The photograph was taken using conventional techniques and although colors may appear different from actual colors due to light reflectance it is as accurate as possible by conventional photographic techniques.

BOTANICAL DESCRIPTION OF THE PLANT

30 The following is a detailed description of the new *Rhododendron* cultivar named 'Hort200101'. Data was collected in Kruishoutem, Belgium from 24 month old greenhouse grown plants in 1.0 liter containers. The time of year was Spring and the average temperature was 22° Centigrade during the day and 18° Centigrade at night. The light level was 5000 Klux and there were no photoperiodic treatments. Color determinations are in accordance with The Royal Horticultural Society Colour Chart 2001 edition, except where general color terms of ordinary dictionary significance are used. The growing requirements are similar to the species. 'Hort200101' has not been tested under all possible conditions and phenotypic differences may be observed with variations in environmental, climatic, and cultural conditions, however, without any variance in genotype.

Botanical classification: <i>Rhododendron simsii</i> 'Hort200101'.		Flowering habit.—Continuously once a year.
Use: Ornamental Perennial Shrub.		Quantity of flowers per lateral stem.—Approximately 5.
Parentage: 'Hort200101' is a hybrid of the female or seed parent a proprietary selection of <i>Rhododendron simsii</i> identified as '97468' and the male or pollen parent a proprietary selection of <i>Rhododendron simsii</i> identified as '93085'.	5	Quantity of flower buds per lateral stem.—Approximately 1 to 5.
Vigor: Moderately strong		Quantity of flowers and buds per plant.—Approximately 60.
Growth rate: Approximately 8 cm. in height and 15 cm. in width per year.	10	Flowering season.—February to April.
Growth habit: Broad upright, densely branched.		Time to flower or response time.—2 to 4 weeks depending on temperature regime.
Plant shape: Flattened globose.		Rate of flower opening.—After the first flower of a cluster has opened, all flowers of that cluster will open in approximately 14 days.
Suitable container size: 1.0 liter container.		Fragrance.—None.
Height: Average 27 cm. in height.	15	Self-cleaning or persistent.—Persistent.
Width: Average 40 cm. in width.		Flower bud length.—9 mm. in length.
Hardiness: 0° to 40° C.		Flower bud diameter.—7 mm. in diameter.
Propagation: Cuttings.		Flower bud shape.—Ovate.
Time to initiate roots: Approximately 30 days to produce roots on an initial cutting.	20	Rate of bud opening.—10 days.
Time to produce a rooted cutting or liner: Approximately 60 days.		Flower aspect.—Upright.
Root system: Fine and fibrous.		Flower shape.—Funnelform.
Stem:		Flower dimensions.—5.5 cm. in diameter and 2.5 cm. in height.
<i>Branching habit</i> .—Freely branching.		Flower longevity.—Lasts approximately 21 days on plant.
<i>Average number of lateral branches</i> .—3.	25	Petal appearance.—Dull, slight velvety.
<i>Pinching</i> .—Yes.		Petal texture.—Glabrous.
<i>Lateral branch diameter</i> .—3 mm. in diameter.		Petal arrangement.—Funnelform, rosette.
<i>Lateral branch length</i> .—11 cm. in length.		Number of petals.—Approximately five in number.
<i>Lateral branch strength</i> .—Moderately strong.		Petals fused or unfused.—Fused.
<i>Stem color</i> .—185A.	30	Petal shape.—Obovate.
<i>Pubescence</i> .—Dense, short.		Petal margin.—Entire.
<i>Internode length</i> .—8 mm. between nodes.		Petal apex.—Rounded.
<i>Shape</i> .—Round.		Petal dimensions.—2.1 cm. in length and 1.8 cm. in width.
<i>Surface</i> .—Dull.		Petal color when opening (upper side).—53B.
<i>Stem strength</i> .—Moderately strong.	35	Petal color when opening (under side).—53B.
Foliage:		Petal color when fully opened (upper side).—53B with 46A on the throat.
<i>Texture</i> .—Very glossy, slightly leathery.		Petal color when fully opened (under side).—53B.
<i>Leaf arrangement</i> .—Alternate, clustered towards the top of the stems.		Petal color fading to.—Not fading.
<i>Compound or single</i> .—Single.	40	Calyx:
<i>Quantity of leaves per lateral branch</i> .—16.		<i>Calyx shape</i> .—Rounded.
<i>Leaf shape</i> .—Elliptic.		Sepals:
<i>Leaf apex</i> .—Obtuse.		<i>Sepal appearance</i> .—Dull, pubescent.
<i>Leaf base</i> .—Acute.		<i>Number of sepals</i> .—Five in number.
<i>Leaf length</i> .—3.8 cm. in length.	45	<i>Sepals fused or unfused</i> .—Fused.
<i>Leaf width</i> .—1.5 cm. in width.		<i>Sepal shape</i> .—Ovate.
<i>Pubescence</i> .—Absent.		<i>Sepal margin</i> .—Entire.
<i>Leaf margin</i> .—Entire.		<i>Sepal dimensions</i> .—2 mm. in length and 2 mm. in width.
<i>Vein pattern</i> .—Pinnate.		50 Reproduction organs:
<i>Young leaf color (upper surface)</i> .—141A.		<i>Stamen number</i> .—1.
<i>Young leaf color (lower surface)</i> .—141B.		<i>Anther shape</i> .—Fused to petals.
<i>Mature leaf color (upper surface)</i> .—131A.		<i>Pistil number</i> .—1 in number.
<i>Mature leaf color (lower surface)</i> .—131A.		<i>Pistil dimensions</i> .—2.0 cm. in length.
<i>Vein color (lower surface)</i> .—131B.		<i>Stigma shape</i> .—Club shaped.
<i>Vein color (upper surface)</i> .—131B.	55	<i>Stigma color</i> .—155C.
<i>Leaf attachment</i> .—Petiolate.		<i>Style length</i> .—1.7 cm.
<i>Petiole dimensions</i> .—8 mm. in length, slightly flattened 2 mm. in width, 1 mm. in height.		Seed: Seed production has not been observed to date.
<i>Petiole color</i> .—143C.		Disease and pest resistance: Plants of the new <i>Rhododendron</i> have not been observed for disease or pest resistance.
<i>Durability of foliage to stress</i> .—Moderate.	60	The invention claimed is:
Flower:		1. A new and distinct variety of <i>Rhododendron</i> plant named Hort200101 as described and illustrated.
<i>Flower arrangement</i> .—Terminal clusters.		
<i>Inflorescence type</i> .—Funnelform.		
<i>Inflorescence dimensions</i> .—9 cm. in diameter and 5 cm. in height.	65
